(57) **CLAIM**

The ornamental design for a paint brush handle, as shown and described.

DESCRIPTION

FIG. 1 is a front elevation view of a first embodiment of a paint brush handle, embodying our new design;

FIG. 2 is a side elevation view thereof;

FIG. 3 is a top perspective view thereof;

FIG. 4 is a side perspective view thereof;

FIG. 5 is a front elevation view of a second embodiment of a paint brush handle, embodying our new design;

FIG. 6 is a side elevation view thereof;

FIG. 7 is a top perspective view thereof; and,

FIG. 8 is a side perspective view thereof.
